FREDERIC BILLON, OF SOLOTHURN, SWITZERLAND.

ELECTRIC IGNITION APPARATUS.

1,361,133.

Specification of Letters Patent.

Patented Dec. 7, 1920.

Application filed December 5, 1917. Serial No. 205,689.

To all whom it may concern:

Be it known that I, FREDERIC BILLON, a citizen of the Swiss Republic, residing at Solothurn, Switzerland, have invented certain new and useful Improvements in Electric Ignition Apparatus, of which the following is a specification.

This invention relates to a new manner of constituting the magnetic circuit in electric ignition apparatus for internal combustion engines which will allow of producing per revolution of the apparatus any desired number of current impulses at any desired intervals of time without necessitating the employment of a rotary intermediate member of magnetically conducting material (hitherto required for this purpose) which has an unfavorable influence upon the resistance of the magnetic circuit and consequently upon the dimensions of the apparatus.

The constitution of the magnetic circuit of the apparatus for this purpose is such that for each pole of the stationary part, a determined number of pole pieces are employed which are staggered relatively to one another and to the pole pieces of the other pole in the direction of the rotation of the rotating part, and which are also shifted axially in relation to one another in such a manner that the pieces of the one pole are divided into two groups and arranged symmetrically at both sides of those of the other pole. The pole pieces of the rotating part are on the contrary arranged in such number and staggered relatively to one another at such angles as to produce the requisite number of current impulses at suitable intervals of time.

Some constructional forms of the subject matter of this invention are illustrated by way of example in the accompanying drawings in which:

Figure 1 is a cross section at right angles to the axis, and

Figs. 2 and 3 are perspective views of the stationary and rotating parts of the magnetic circuit for an ignition apparatus which produces four current impulses per revolution.

Fig. 4 is a developed view of the stator and rotor; from this figure it will be seen that four current impulses follow each other at equal intervals of time during each entire revolution.

Fig. 5 illustrates the arrangement for pro-

ducing six current impulses for each revolution of the apparatus for the ignition of six-cylinder engines.

Fig. 6 illustrates an arrangement in which only one pole piece is formed on the middle limb, as well as on the two outer limbs.

Figs. 7 and 8 show two different positions of the rotor relatively to the stator.

The rotor (Figs. 1 and 3) consists of a permanent magnet comprising two pole pieces N and S which are spaced 90° to each other and to which there are opposed in all six pole pieces on the stator. These are arranged in pairs diametrically opposite to each other in such a manner that one pair A B embraces the rotor in the middle, while the other two pairs C D and E F are located symmetrically at the two sides of the middle pair, and are both spaced through 90° relatively to the said middle pair. G H are counterweights for balancing the pole pieces N and S on the rotor.

In the arrangement shown in Fig. 5 the stationary part of the magnetic circuit embraces the rotating part, as shown in Fig. 2, with a middle arm and with two arms located symmetrically on the two sides of the middle arm. Each of the two side arms is provided with three pole pieces spaced 120° apart. The rotating portion comprises two pole pieces N and S located at 60° apart which are balanced by suitably arranged counterweights, otherwise the two pole pieces may be arranged at 180° apart, and in this case no balancing by counterweights is required.

By suitably selecting the number and position of the pole pieces on the stationary and rotating parts of the magnetic circuit, it is possible to produce any desired number of and any desired intervals of time between, the current impulses during each revolution. For example, only one maximum change of lines of force is produced in the yoke, and consequently only one maximum current impulse is produced per revolution with the help of the arrangement shown in Fig. 6. The stationary portion of the magnetic circuit has in this arrangement only one pole piece (B and C respectively) on its middle limb as well as on the two outer limbs, of which the two outer pole pieces C and D, or the middle pole piece B, almost completely embrace the periphery of the rotating portion, while the other pole piece engages in the gap which

is thereby formed. The rotary portion has two pole pieces N and S arranged at corresponding angles apart, with counterweights G, H as shown.

- 5 By making the angles embraced by the pole pieces unequal, and shifting them relatively in the rotary direction, the result is obtained that the current impulses produced during one revolution follow one another 10 at unequal intervals of time in accordance with the cylinder angle in two-cylinder engines.

Constructions of this kind are shown in Figs. 7 and 8. These figures show two different positions of the rotating portion relatively to a stationary portion which comprises on the one hand pole pieces in the position and extent indicated at A and B, and on the other hand pole pieces in the 20 position and extent indicated at E and F. The pole pieces, for example A and B, belonging to one and the same pole, are in this case arranged apart at an angle of 180° plus or minus the half cylinder angle α . 25 Consequently the current impulses follow one another at corresponding unequal intervals of time. In the same manner as by the dimensioning and arrangement of the pole pieces on the stationary portion of the 30 magnetic circuit, it is possible to influence the number and time-succession of the current impulses also by suitable dimensioning and arrangement of the pole pieces of the rotating portion of the apparatus. In this 35 arrangement the rotating portion (Fig. 3) may be constituted by a permanent magnet which in rotating sends out lines of force in varying direction through the yoke (Fig. 2) which is constructed as the stationary 40 portion and carries the induction coil, or the said yoke may consist of a permanent magnet whose pole pieces embrace the ro-

tating portion of the apparatus, which said rotating portion is constructed as an I-armature and carries the induction coil. 45

What I claim is:—

1. In the magnetic circuit of an ignition apparatus for internal combustion engines, the combination of a stator comprising for each of its poles, a determined number of 50 pole pieces comprising a central pole piece and a plurality of divided pole pieces, said pole pieces respectively being spaced axially relatively to one another, and to the pole pieces of the adjacent pole in the direction 55 of the rotation of the rotor, so that the pole pieces of one pole are divided into two groups and located symmetrically at both sides of the central pole piece, and a rotor comprising pole pieces placed at determined 60 angles relatively to one another, whereby a desired number of current impulses are produced with desired intervals of time between them during each revolution of the rotor, substantially as described. 65

2. In the magnetic circuit of an ignition apparatus for internal combustion engines, the combination of a stator comprising for each of its poles, two pole pieces located diametrically opposite each other and spaced 70 90° relatively to the pole pieces of the adjacent pole in the direction of the rotation of the rotor, so that the pole pieces of one pole are divided into two groups and located 75 symmetrically at both sides of the pole pieces of the other pole, and a rotor comprising two pole pieces spaced 90° relatively to each other, whereby four current impulses are produced with equal intervals of time between them during each revolution of the rotor. 80

In testimony whereof I have signed my name to this specification.

FREDERIC BILLON.
